(57) **ABSTRACT**

In an embodiment an X-ray source includes an electron source configured to emit electrons, an acceleration set-up configured to accelerate the emitted electrons and a transmission window downwards of the acceleration set-up, wherein the transmission window is configured to let through X-rays generated by the accelerated electrons, wherein the transmission window is located either in a straight extension of a line-of-flight of the accelerated electrons or off the line-of-flight and past the acceleration set-up, wherein the transmission window comprises a carbon carrier, and wherein the carbon carrier comprises sp₂-hybridized carbon.

X-RAY SOURCE

CROSS-REFERENCE TO RELATED APPLICATIONS

This application is a continuation-in-part application of U.S. application Ser. No. 17/821,641, filed on Aug. 23, 2022, which application is hereby incorporated herein by reference.

TECHNICAL FIELD

An X-ray source is provided.

BACKGROUND

U.S. Pat. No. 9,257,254 B2 and U.S. Pat. No. 10,229,808 B2 refer to transmission targets.

Document “PGS” Graphite Sheets’ from Panasonic, Dec. 5, 2013, describes sheets of pyrolytic graphite.

Document Isaac Childres et al., “Raman spectroscopy of graphene and related materials”, New developments in photon and materials research, 1, from 2013, refers to Raman spectroscopy of differently hybridized carbon.

SUMMARY

Embodiments provide an X-ray source for efficient emission of X-rays.

For example, the X-ray source described herein comprises a transmission window having a carbon carrier of sp₂-hybridized carbon that may carry a target layer, for example. This allows a comparable low-energy transmission performance to beryllium, without the toxicity.

According to at least one embodiment, the X-ray source comprises one or a plurality of electron sources configured to emit electrons. The at least one electron source can be any one of a field emitter, a thermal emitter, a gate-insulator-substrate structure for emitting hot electrons and/or may work based on triboluminescence or Piezo effect. If there is a plurality of electron sources, as an option different types of electron sources can be combined with each other.

According to at least one embodiment, the X-ray source comprises one or a plurality of acceleration set-ups. The at least one acceleration set-up is configured to accelerate the electrons emitted by the at least one electron source. For example, the at least one acceleration set-up comprises at least two electrodes to accelerate the emitted electrons. It is further possible that the at least one acceleration set-up includes electron optics and/or at least one further electrode in order to define a path of the emitted electrons and/or of the already accelerated electrons. It is not necessary that all the electrons run along the same path.

According to at least one embodiment, the X-ray source comprises one or a plurality of transmission windows. The at least one transmission window is located downwards of the at least one acceleration set-up, that is, for example, the transmission window is located after the at least one acceleration set-up seen along a path of at least one of the accelerated electrons or the X-rays produced. The at least one transmission window is configured to be passed by X-rays generated by the accelerated electrons, for example, next to or at the at least one transmission window.

According to at least one embodiment, the at least one transmission window comprises one or a plurality of carbon carriers. The, for example, exactly one carbon carrier is that component of the transmission window that mechanically

2

supports and carries the transmission window. In other words, without the carbon carrier the transmission window would be mechanically not stable in the intended use of the transmission window.

According to at least one embodiment, the carbon carrier comprises sp₂-hybridized carbon. For example, most of the carbon of the carbon carrier is present as sp₂-hybridized. Thus, the carbon carrier has a high proportion of graphene-like bound carbon.

In at least one embodiment, the X-ray source comprises: an electron source configured to emit electrons, an acceleration set-up configured to accelerate the emitted electrons, and

a transmission window downwards of the acceleration set-up and through which X-rays generated by the accelerated electrons are led, wherein the transmission window comprises a carbon carrier, and wherein the carbon carrier comprises sp₂-hybridized carbon.

An important cost-factor of manufacturing X-ray tubes are the costs of a transmission window used. Usually, a beryllium window is used. Beryllium is suitable because it is an element with a low atomic mass, is electrically and thermally conductive and can be machined. For example,

thicknesses of beryllium of about 125 µm are used. In addition, a metal layer at the beryllium window is used as a target layer, if necessary with an adhesion promoter, to generate the actual X-rays with characteristic X-ray energies suitable for the respective application. Due to the small thickness of the beryllium window, a high transmission in particular of a low-energy spectral component of the X-rays is possible. However, beryllium has the disadvantage that it is highly toxic and very expensive to produce.

In the X-ray source described herein, the beryllium window is replaced with graphitized carbon that has a high sp₂ bond content. Depending on the production method, this allows mechanically stable and electrically as well as thermally conductive films to be realized as the carrier. Such films can also be used as a heat spreader in circuits because of its very high thermal conductivity and because such films are cheaper to obtain than beryllium. Further, such a solution for an X-ray transmission window avoids the health concerns and leads to significantly lower manufacturing costs. A higher tube power than with previous tubes based on beryllium windows is also conceivable due to the very high thermal conductivity of sp₂-hybridized carbon.

Since different target metals are used in different applications and the best possible adhesion to the carbon carrier is required, various intermediate layers between the carbon carrier and a target layer may be necessary to realize this.

According to at least one embodiment, a mass proportion of carbon of the carbon carrier is at least 60% or is at least 85% or is at least 95% or is at least 99%. It is possible that the carbon carrier consists of carbon.

According to at least one embodiment, a mass proportion of carbon of the transmission window in an area configured to be passed by the X-rays is at least 60% or is at least 85% or is at least 90% or is at least 95% or is at least 99%. In other words, in the area to be passed by the X-rays generated by the accelerated electrons, the transmission layer may consist or may essentially consist of the carbon layer. This applies, for example, if the transmission window is configured as a side window.

According to at least one embodiment, the carbon of the carbon carrier is predominantly sp₂-hybridized. This means, for example, that in a deconvoluted Raman spectrum of the carbon carrier the 2D-peak has by at least a factor of 1.5 or

by at least a factor of two or by at least a factor of five or by at least a factor of ten or by at least a factor of 50 a larger area content than the sp₃-peak.

The D-peak, also referred to as G'-peak, is in the range between 2650 cm⁻¹ and 2750 cm⁻¹, for example, measured with laser excitation at 532 nm. For example, the sp₃-peak, also referred to as defect peak, is located in a range between 1250 cm⁻¹ and 1350 cm⁻¹. Deconvolution of the Raman spectrum is done, for example, by one Gaussian fit per relevant peak.

The areas of the peaks, that is, the area content of the respective Gaussian curve fit, is a measure for the Raman intensity of the respective peak. The ratio of the intensities of the peaks roughly corresponds to a ratio of sp₃ and sp₂ bonds content in the carbon carrier.

According to at least one embodiment, the carbon carrier is of one or of a mixture of the following materials: graphene, multi-layer graphene, bi-layer graphene, tri-layer graphene, exfoliated graphene, few-layer graphene, graphene-based material, graphene-family material, nano-crystalline graphene, pyrolytic graphene, pyrolytic carbon, graphitic carbon, graphenic carbon, glassy carbon, pyrolyzed polymer film, crystallized two-dimensional carbon, layered sheet of crystallized two-dimensional carbon, highly oriented pyrolytic graphite (HOPG), nature-graphite with hexagonal structure.

According to at least one embodiment, the carbon carrier comprises or consists of pyrolytic carbon.

The following values may apply at an atmospheric pressure of 1013 mbar and at a temperature of 300 K.

According to at least one embodiment, a thermal conductivity of the carbon carrier is at least 0.4 kW/(m·K) and/or is at most 3 kW/(m·K). Furthermore, it is possible that the thermal conductivity is inhomogeneous and has different values along different directions. For example, the thermal conductivities along at least two directions of the material differ from one another by at least a factor of 2 or by at least a factor of 5 or by at least a factor of 10 or by at least a factor of 30 or by at least a factor of 100.

Here and in the following, the different directions concerning the inhomogeneity can be two different directions within a plane of main extent of the carbon carrier; for example, an angle between said directions is 45° or is 60° or is 90°. Otherwise, the different directions concerning the inhomogeneity can refer to one direction within the plane of main extent and to a direction perpendicular to said plane, that is, to a first direction in the plane of the carbon carrier and to a second direction along a thickness direction of the carbon carrier, perpendicular to the first directions. Furthermore, the two directions can be aligned in any way possible in said plane.

According to at least one embodiment, a Young's modulus, also referred to as E modulus, of the carbon carrier is at least 2 GPa and/or is at most 200 GPa.

According to at least one embodiment, a density of the carbon carrier is at least 0.5 g/cm³ and/or is at most 2.5 g/cm³.

According to at least one embodiment, an electrical conductivity of the carbon carrier is at least 0.1 kS/m and/or is at most 1 MS/m. Furthermore, it is possible that the electrical conductivity is inhomogeneous and has different values along different directions. For example, the electrical conductivities along at least two directions of the material differ from one another by at least a factor of 2 or by at least a factor of 5 or by at least a factor of 10 or by at least a factor of 30 or by at least a factor of 100.

According to at least one embodiment, a tensile strength of the carbon carrier is at least 1 MPa and/or is at most 100 MPa. Furthermore, it is possible that the tensile strength is inhomogeneous and has different values along different directions. For example, the tensile strengths along at least two directions of the material differ from one another by at least a factor of 2 or by at least a factor of 5 or by at least a factor of 10 or by at least a factor of 30 or by at least a factor of 100.

According to at least one embodiment, the carbon carrier is capable of at least 103 and/or of at most 105 bending cycles. Per bending cycle, the carbon carrier is subject to a 180° bending.

According to at least one embodiment, the carbon carrier is capable of shielding electric or magnetic fields.

According to at least one embodiment, the carbon carrier is resistant to temperatures of at least 250° C. or of at least 450° C. or of at least 1000° C. or of at least 3000° C.

According to at least one embodiment, the carbon carrier is manufactured by one or by a plurality of the following methods:

Chemical Vapor Deposition (CVD), like Atmospheric Pressure CVD (APCVD), Low-Pressure CVD (LPCVD), Plasma-Enhanced CVD (PECVD) or Ethanol-Catalytic CVD (ECCVD),

Physical Vapor Deposition (PVD), like thermal deposition or electron-beam deposition or arc-PVD, transfer methods, catalytic deposition, solid phase graphenization, like pyrolysis in combination with annealing.

In at least one embodiment, the X-ray source comprises an electron source configured to emit electrons, an acceleration set-up configured to accelerate the emitted electrons, and

a transmission window downwards of the acceleration set-up and through which X-rays generated by the accelerated electrons are led, the transmission window is located either in straight extension of a line-of-flight of the accelerated electrons or off the line-of-flight and past the acceleration set-up,

wherein the transmission window comprises a carbon carrier, and wherein the carbon carrier comprises sp₂-hybridized carbon.

For example, in case the transmission window is located off the line-of-flight and past the acceleration set-up, the transmission window is a side window. Thus, the accelerated electrons may be led away from the transmission window.

According to at least one embodiment, the X-ray source further comprises one or a plurality of target layers. For example, the at least one target layer is carried by the at least one carbon carrier. However, alternatively it is also possible that the transmission window is free of any target layer, for

example, free of any metallic layer configured for generating X-rays. In this case, the x-rays would be generated in the membrane itself, or there is a target layer distant from the carbon layer and/or distant from the transmission window so that the target layer does not need to touch the transmission layer.

According to at least one embodiment, the at least one target layer is located on a side of the carbon carrier facing the electron source.

According to at least one embodiment, the transmission window is located in straight extension of the line-of-flight of the accelerated electrons. This applies, for example, if the carbon carrier carries the target layer.

According to at least one embodiment, the target layer is thicker than the carbon layer. This applies, for example, if the transmission window is off the line-of-flight and is a side window. Thus, the target layer can be made mostly independently of the transmission window and, thus, does not need to be transmissive for the X-rays to be generated.

According to at least one embodiment, the target layer is located within a housing of the X-ray source. For example, the housing comprises an opening closed by the transmission window and/or closed by the transmission window together with a window frame.

According to at least one embodiment, the at least one target layer comprises or consists of one or of a plurality of metals. For example, the at least one target layer is of one of the following metals: Rh, W, Ag, Ti, Mo, Pt, Pd, Au. It is possible that there are target layers of different metals.

According to at least one embodiment, the at least one target layer is thinner than the at least one carbon carrier. For example, a thickness of the carbon carrier exceeds a thickness of the target layer by at least a factor of 1.5 or by at least a factor of 10 or by at least a factor of 50 and/or by at most a factor of 100 or by at most a factor of 100.

According to at least one embodiment, the thickness of the target layer is at least 1 nm or is at least 10 nm or is at least 50 nm. Alternatively or additionally, said thickness is at most 5 μ m or is at most 1 μ m or is at most 0.2 VIM.

According to at least one embodiment, the thickness of the carbon carrier is at least 0.1 μ m or is at least 1 μ m or is at least 20 μ m. Alternatively or additionally, said thickness is at most 2 mm or is at most 0.1 mm or is at most 40 μ m.

For example, in case the transmission window is located off the line-of-flight the carbon layer may be particularly thin. This may mean that the thickness of the carbon layer is at most 10 μ m or is at most 5 μ m or is at most 3 μ m.

Alternatively or additionally, the thickness of the target layer thickness is at most 5 μ m or is at most 10 μ m and a thickness of the carbon carrier is between 0.02 mm and 2 mm. This applies, for example, if the transmission window is on the line-of-flight of the accelerated electrons.

According to at least one embodiment, the target layer is directly applied on the carbon carrier. For example, all of the face of the target layer facing the carbon carrier touches the carbon carrier.

According to at least one embodiment, the transmission window further comprises one or a plurality of bonding layers. The at least one bonding layer is located between the target layer and the carbon carrier. For example, the target layer and the carbon carrier are separated from one another by the respective bonding layer and are both in direct contact with the bonding layer, for example, with their complete faces facing the respective bonding layer.

Thus, the target layer may be configured to be hit by the accelerated electrons and the carbon layer is configured to be passed by the X-rays generated upon impact of the accelerated electrons on the target layer.

According to at least one embodiment, the at least one bonding layer is of at least one inorganic material. For example, the at least one bonding layer or at least one of the bonding layers is a metallic layer and comprises or consists of one or of a plurality of metals selected from the following group: Cr, Ti, Au, Ni, Pt, Al. Alternatively or additionally, the at least one bonding layer or at least one of the bonding layers is a nitride layer and comprises or consists of one or of a plurality of the following materials: SiN, TiN. Alternatively or additionally, the at least one bonding layer or at least one of the bonding layers is a carbide layer and comprises or consists of one or of a plurality of the following

materials: SiC, a carbide of the metal of the associated target layer. Alternatively or additionally, the at least one bonding layer or at least one of the bonding layers is a semiconductor layer and comprises or consists of one or of a plurality of the following materials: poly-Si, amorphous Si, crystalline Si.

According to at least one embodiment, a thickness of the at least one bonding layer is at least 1 nm or is at least 10 nm. Alternatively or additionally, said thickness is at most 1 μ m or at most 0.1 μ m or at most 20 nm.

According to at least one embodiment, a diameter of the carbon carrier and/or of the transmission window is at least 1 mm or is at least 4 mm or is at least 6 mm. Alternatively or additionally, said diameter is at most 10 cm or is at most 3 cm or at most 10 mm.

According to at least one embodiment, the X-ray source is free of any auxiliary structures supporting a central part of the transmission window, seen in top view. The central part is that part of the transmission window where a focal spot of the accelerated electrons is located, seen in top view of the transmission window. In other words, the transmission window and/or the X-ray source is free of supporting structures like bars or ridges located in the central part.

According to at least one embodiment, the focal spot of the accelerated electrons at the transmission window has a diameter of at least 0.04 mm or of at least 0.1 mm or of at least 0.25 mm and/or of at most 4 mm. In this case, for example, the X-ray source is configured for X-ray fluorescence spectroscopy (XRF) or for imaging applications.

According to at least one embodiment, the focal spot of the accelerated electrons at the transmission window has a diameter of at least 2 mm or of at least 5 mm and/or of at most 20 mm. In this case, for example, the X-ray source is configured for ion mobility spectroscopy (IMS).

According to at least one embodiment, an area between the electron source and the transmission window is evacuated. This means, for example, that a pressure within the X-ray source, for example, after sufficient operation like a burn-in, and possibly directly at the transmission window is below 10^{-2} mbar or is below 10^{-4} mbar or is below 10^{-6} mbar or is below 10^{-8} mbar. Alternatively or additionally, said pressure is at least 10^{-9} mbar. These values apply, for example, at a temperature of the X-ray source of 300 K.

According to at least one embodiment, a side of the transmission window remote from the electron source is configured to be at a pressure of 1 bar at 300 K. That is, the X-ray source is configured to be operated with the transmission window at normal atmosphere, for example.

According to at least one embodiment, the transmission window is of plane-parallel fashion, overall or at least in the central part. Hence, at least across the central part the transmission window can be of constant thickness. It is possible that an edge part of the transmission window directly around the central part has a reduced or increased thickness in order to provide improved mounting of the transmission window. However, also all over the edge part the thickness of the transmission window can be constant. It is possible that the transmission window consists of the central part and of the edge part, seen in top view.

According to at least one embodiment, the X-ray source is configured for an operating power, for example of the electron source, of at least 10 mW or of at least 0.1 W. Alternatively or additionally, said operating power is at most 1 kW or is at most 0.1 kW.

According to at least one embodiment, an inner diameter and/or an outer diameter of the X-ray source is at least 1 mm or is at least 8 mm. Alternatively or additionally, said diameters are at most 10 cm or are at most 1 cm.

According to at least one embodiment, an inner length and/or an outer length of the X-ray source is at least 0.5 cm or is at least 2 cm. Alternatively or additionally, said lengths are at most 20 cm or are at most 4 cm.

According to at least one embodiment, the carbon carrier is optically non-transparent in the visible spectral range. For example, the carbon carrier has an absorption coefficient of at least 10^6 cm^{-1} or of at least 105 cm^{-1} or of at least 104 cm^{-1} or of at least 103 cm^{-1} ; this applies, for example, in the visible spectral range, like at a wavelength of 600 nm.

According to at least one embodiment, the X-ray source further comprises one or a plurality of window frames. The at least one window frame carries the corresponding at least one transmission window. The window frame can be a single piece or can be of multi-part fashion.

According to at least one embodiment, the at least one window frame is attached on the at least one acceleration set-up. That is, the at least one window frame can be mechanically carried and/or fixed by the at least one acceleration set-up.

According to at least one embodiment, the window frame is attached on a side of a tube of the housing remote from the electron source. That is, said tube may be closed with the window frame and, hence, with the transmission layer. In said window frame, the target layer may be located as well. This is possible in both configurations, that is, when the target layer is part of the transmission window or when the target layer is distant from the transmission window.

According to at least one embodiment, the X-ray source is configured for one or a plurality of the following applications: XRF, IMS, X-ray diffraction (XRD), X-ray topography (XRT), X-ray crystallography (XRC), computer tomography (CT), radiography imaging, electron capture detection (ECD), medical. This may mean that an operating power, an emission spectrum, an emission angle range and/or an emission noise of the emitted X-rays fits the parameters required by the respective application.

In at least one embodiment, the X-ray source comprises an electron source configured to emit electrons, an acceleration set-up configured to accelerate the emitted electrons, and

a transmission window downwards of the acceleration set-up and through which X-rays generated by the accelerated electrons are led,

wherein the transmission window comprises a carbon carrier,

wherein the carbon carrier comprises sp₂-hybridized carbon, and

wherein the acceleration set-up is configured for an acceleration voltage of at most 5 kV or of at most 3 kV or of at most 2 kV or of at most 1 kV or of at most 1.5 kV or of at most 1.1 kV or of at most 0.4 kV.

In this case, for example, the thickness of the carbon layer is at most 10 μm or is at most 5 μm or is at most 2 μm . Hence, with the acceleration voltage being particularly low, the carbon layer and the transmission window in the relevant area is particularly thin as well.

According to at least one embodiment, the X-ray source further comprises an electronics unit. For example, the electronics unit is an acceleration voltage unit. Thus, the electronics unit may be configured to provide the acceleration voltage.

According to at least one embodiment, a low-voltage side and a high-voltage side of the electronics unit are connected by a one-stage voltage changer. Hence, the electronics unit for providing the acceleration voltage may be free of any multi-stage voltage or current generation. Thus, the elec-

tronics unit can be composed of fewer parts and also of parts that need to withstand only relatively low voltages.

According to at least one embodiment, in an intended operation of the X-ray source, the carbon layer is configured to be electrically an anode. Otherwise, the carbon layer can be configured to be electrically on ground.

According to at least one embodiment, the transmission window is provided with at least one protection layer, for example, on a side facing away from the electron source.

Otherwise, it is possible that the side of the transmission window facing away from the electron source is made of the carbon carrier.

According to at least one embodiment, the carbon carrier serves as the target layer. That is, the carbon carrier itself is used to produce X-rays by being hit by the accelerated electrons. The generated X-rays are, for example, of the characteristic carbon X-ray line. In this case, the transmission window and especially the carbon carrier can be the only target for the accelerated electrons. It is possible that the carbon carrier is provided at the side facing away from the electron source with the protection layer. An energy of the X-rays corresponding to the characteristic carbon line may thus be between 276 eV and 279 eV, depending on the carbon used for the carbon carrier, for example.

In at least one embodiment, the X-ray source comprises an electron source configured to emit electrons, an acceleration set-up configured to accelerate the emitted electrons, and

a transmission window downwards of the acceleration set-up and through which X-rays generated by the accelerated electrons are led, the transmission window is located off a line-of-flight of the accelerated electrons and past the acceleration set-up,

wherein the transmission window comprises a carbon carrier,

wherein the carbon carrier comprises sp₂-hybridized carbon,

wherein the acceleration set-up is configured for an acceleration voltage of at most 1 kV,

wherein the transmission window is a side window, for example, the carbon carrier is of pyrolytic carbon, wherein a thickness of the carbon layer is at most 10 μm , wherein a mass proportion of carbon of the transmission window in an area configured to be passed by the X-rays is at least 90%, and

wherein a low-voltage side and a high-voltage side of an electronics unit are connected by a one-stage voltage changer, the electronics unit is configured to provide the acceleration voltage.

A transmission window is additionally provided. The transmission window is configured for an X-ray source as indicated in connection with at least one of the above-stated embodiments. Features of the transmission window are therefore also disclosed for the X-ray source and vice versa.

In at least one embodiment, the transmission window is configured for an X-ray source and comprises:

a carbon carrier that comprises sp₂-hybridized carbon, and

a target layer carried by the carbon carrier, wherein the target layer is of at least one metal and is thinner than the carbon carrier.

An operation method is additionally provided. By means of the operation method, an X-ray source as indicated in connection with at least one of the above-stated embodiments is operated. Features of the operation method are therefore also disclosed for the X-ray source and vice versa.

In at least one embodiment, the method comprises the following step:

Providing the X-ray source, and

Operating the X-ray source with an acceleration voltage.

For example, the acceleration voltage is at most 5 kV or is at most 3 kV or is at most 2 kV or is at most 1 kV or is at most 1.5 kV or is at most 1.1 kV or is at most 0.4 kV. Alternatively or additionally, the acceleration voltage is at least 0.3 kV or is at least 0.8 kV. Hence, the acceleration voltage can be relatively low.

An X-ray source and an operation method described herein are explained in greater detail below by way of exemplary embodiments with reference to the drawings. Elements which are the same in the individual figures are indicated with the same reference numerals. The relationships between the elements are not shown to scale, however, but rather individual elements may be shown exaggeratedly large to assist in understanding.

BRIEF DESCRIPTION OF THE DRAWINGS

FIGS. 1 and 2 show schematic sectional views of exemplary embodiments of X-ray sources described herein;

FIGS. 3 and 4 are schematic sectional views of exemplary embodiments of transmission windows for X-ray sources described herein;

FIG. 5 shows a schematic representation of the G-peak and the D-peak of exemplary embodiments of transmission windows for X-ray sources described herein;

FIG. 6 is a schematic sectional view of an exemplary embodiment of an X-ray source described herein;

FIG. 7 is a schematic block diagram of an electronics unit for providing an acceleration voltage for exemplary embodiments of X-ray sources described herein;

FIG. 8 is a schematic representation of X-ray emission spectra of exemplary embodiments of X-ray sources described; and

FIG. 9 herein is a schematic block diagram of an exemplary embodiment of an operation method for X-ray sources described herein.

DETAILED DESCRIPTION OF ILLUSTRATIVE EMBODIMENTS

FIG. 1 illustrates an exemplary embodiment of an X-ray source 1. The X-ray source 1 comprises a housing 5 with a base plate 53 through which a pin 55 is led. The pin 55 carries an electron source 2, which is, for example, a filament that may be heated. The base plate 53 can be housed in a socket 54 of the housing 5. Optionally, at the socket 54 there is an outer tube 52 of the housing 5. It is possible that the socket 54 and the first electrode 31 are of one single piece.

The electron source 2 is configured to emit electrons 22. Downstream of the electron source 2, there is a first electrode 31 of an acceleration set-up 3. The first electrode 31 may be in one piece with the socket 54. Further, downstream of the first electrode 31 there is a second electrode 32 of the acceleration set-up 3. The acceleration set-up 3 is configured to accelerate the emitted electrons 22 along a direction away from the electron source 2, for example. Thus, the electrons 22 run through the second electrode 32 so that the latter can be a transmission anode.

A relative position between the electrodes 31, 32 is defined by an inner tube 51 of the housing 5. Thus, the inner tube 51 may hold the second electrode 32.

For example, within the inner tube 51 into which the first electrode 31 and the pin 55 carrying the electron source 2 protrude, there is an evacuated area 56 maintaining a pressure in the sub-mbar range. The outer tube 52 may reach beyond the first electrode 31, starting from the socket 54, but may not reach up to the second electrode 31 that also protrudes into the inner tube 51 but from an opposite direction. The second electrode 32 may cover end faces of the inner tube 51 remote from the base plate 53.

10 Optionally, within an end portion of the second electrode 32 remote from the first electrode 31 there can be a window frame 6. The window frame 6 is configured to fix a transmission window 4 at an end of the inner tube 51. The window frame 6 may be a single piece, for example, like a half of a cylinder. Within the window frame 6, the transmission window 4 is arranged.

For example, the transmission window 4 is glued, sintered, brazed, soldered or welded onto the window frame 6. As an option, hard-soldering, brazing, soft-soldering eutectic soldering or glass soldering may be used as well as laser welding, electron beam welding, friction welding, ultrasonic welding, electric resistance welding or the like. It is possible that at an edge part the window frame 6 and/or the transmission window 4 carries a ring-like connection layer, not shown, for providing adhesion between these two components. Further, there can be a geometric structuring, not shown, at least one of the transmission window 4 and the window frame 6 for mounting the transmission window 4.

By means of the acceleration set-up 3, the electrons 22 are 30 accelerated and optionally also focused onto the transmission window 4. Not shown, for focusing the electrons 22 there can be electron optics, realized, for example, by the shape of the electrodes 31, 32, like the shape of the second electrode 32. Upon impact of the electrons 22 onto the 35 transmission window 4, X-rays X are generated that are emitted by the X-ray source 1 through the transmission window 4. Thus, the X-ray source 1 may also be referred to as an X-ray tube. The generated X-rays X are, for example, characteristic carbon X-rays.

40 The transmission window 4 is not based on beryllium, but is based as its mechanically supporting component on sp2-hybridized carbon as explained in more detail below in connection with FIGS. 3 and 4.

For example for X-ray fluorescence spectroscopy, the 45 X-ray source 1 is configured for an operating power between 0.1 W and 15 W. Additionally, in ion mobility spectroscopy, operating powers down to 1 mW can be used. For example, an electron focal spot of the electrons 22 at the transmission window 4 has a diameter between 0.05 mm and 4 mm 50 inclusive in case of serving for XRF, or may have a diameter between 5 mm and 20 mm inclusive in case of serving for IMS.

In FIG. 1, the X-ray source 1 is of linear design, that is, for example, the electrons 22 and the generated X-rays X are 55 led along a common straight axis. Otherwise, it is also possible that the X-ray source 1 is of angled design so that the electrons 22 and/or the X-rays X may be led along a kinked axis having, for example, a 90° angle, compare also FIG. 6 below. Accordingly, not only transmission anodes but 60 also solid anodes with an additional separate transmission side window can be used. The same applies for all other examples of the X-ray source 1.

In the example of the X-ray source 1 of FIG. 2, the window frame 6 comprises an outer part 61 and an inner part 62. The transmission window 4 is placed between these two parts 61, 62 so that the edge part of the transmission window 4 is fixed in the window frame 6 and can adhesively be

11

connected to both parts 61, 62. As in all other examples, it is possible that the transmission window 4 is of plane-parallel fashion.

Otherwise, the same as to FIG. 1 may also apply to FIG. 2, and vice versa.

In FIGS. 3 and 4, examples of transmission windows 4 are illustrated. In each case, the transmission windows 4 comprise a carbon carrier 41 which is based on sp₂-hybridized carbon and which mechanically carries the transmission windows 4. For example, a thickness of the carbon carrier 41 is between 0.02 mm and 0.1 mm inclusive. For example, a diameter of the carbon carrier 41 is between 5 mm and 9 mm inclusive. Optionally, the carbon carrier 41 is of pyrolytic carbon.

The carbon carrier 41 itself can be used as a target material so that the generated X-rays are characteristic carbon radiation upon impact of the accelerated electrons 22. In this case, the transmission window 4 may consist of the carbon carrier 41, or of the carbon carrier 41 and of at least one protection layer, not shown.

Optionally, if the carbon carrier 41 is not used as the target material, the carbon carrier 41 can carry a distinct target layer 42. Then, the target layer 42 is configured to generate the X-rays upon impact of the electrons 22. For example, the target layer 42 is of one of the following metals: W, Rh, Ag, Au, Mo, Pd. For example, a thickness of the target layer 42 is between 0.05 μm and 10 μm inclusive. The target layer 42 may be thinner than the carbon carrier 41 and may not be self-supporting so that the carbon carrier 41 is needed to mechanically support the target layer 42.

As shown in FIG. 3, the optional target layer 42 is directly applied onto the carbon carrier 41, for example, by sputtering or evaporating. Contrary to that, according to FIG. 4 there is a bonding layer 43 between the carbon carrier 41 and the target layer 42. The bonding layer 43 can be thinner than the target layer 42. For example, the bonding layer 43 is of an oxide, a nitride or of Si.

All the components 41, 42, 43 can be of single-layer fashion. However, as indicated in FIG. 4 by the dashed lines, one or a plurality of the carbon carrier 41, the target layer 42 and the optional bonding layer 43 can be of multi-layer fashion so that there is a plurality of sub-layers in the respective component. These sub-layers may differ from one another in material composition and/or in material configuration, like orientation or crystal lattice, and also in geometric properties, like thickness, lateral extend and/or shape. The same applies for all other examples.

Moreover, based on FIG. 3, a sandwich structure of the transmission window 4 is also possible. That is, for example, the target layer 42 can be located between two of the carbon carriers 41 which may be of the same or of different thicknesses, wherein bonding layers 43 can be present between the layers 41, 42, 41 analogously to FIG. 4.

As a further option, not shown in FIGS. 3 and 4, there can be at least one protection layer on at least one main side of the transmission window 4. By means of the at least one protection layer, the transmission window 4 can be protected from physical or chemical harsh conditions. For example, there is one protection layer at a side of the transmission window 4 facing away from the electron source 2. It is possible that the at least one protection layer is of an oxide or of a nitride, like a silicon oxide or an aluminum nitride. Further, the at least one protection layer may be of multi-layer fashion, for example, may be a combination of an aluminum oxide sub-layer and of a silicon dioxide layer—

12

For example, an overall thickness of the at least one protection layer is at most 50 nm or is at most 10 nm or is at most 4 nm.

Otherwise, the same as to FIGS. 1 and 2 may also apply to FIGS. 3 and 4, and vice versa.

In FIG. 5, a Raman shift S vs. a Raman Intensity I of a Raman spectrum of the carbon carrier 41 is schematically illustrated in the region of the 2D-peak and of the defect-peak, that is around 2700 cm⁻¹ and around 1300 cm⁻¹, respectively. The peaks are fitted by Gaussian curves so that an area content A_{2D} of the 2D-peak and an area content A_{def} of the defect-peak are revealed. These area contents A_{2D}, A_{def} are a measure of the proportions of sp₂-hybridized carbon and sp₃-hybridized carbon. As can be seen from the example in FIG. 5, the area content A_{2D} is about a factor of three larger than the area content A_{def}, for example. Thus, the carbon carrier 41 is predominantly of sp₂-hybridized carbon. This applies, for example, for laser excitation of the carbon carrier at 532 nm.

Concerning Raman spectroscopy of sp₂-hybridized carbon, reference is also made to document Isaac Childres et al., "Raman spectroscopy of graphene and related materials", New developments in photon and materials research, 1, from 2013, as well as to Joe Hodkiewicz, "Characterizing Carbon Materials with Raman Spectroscopy", Thermo Fisher Scientific, Madison, WI, USA, Application Note: 51901. These two references are incorporated herein by reference in their entirety.

In FIG. 6, another embodiment of the X-ray source 1 is shown. In this embodiment, the transmission window 4 is a side window. The target layer 42 is distant from the transmission window 4. Both the target layer 42 and the transmission window 4 can be located in the window frame 6 on top of the inner tube 51 of the housing 5. Thus, the target layer 42 can be comparably thick, and the electrons 22 hit the target layer 42 but not or only in a negligible extent the transmission window 4. The X-rays X produced by the electrons 22 at the target layer 42 are emitted through the transmission window 4. In an area the X-rays X pass through the transmission window 4, the latter may consist of the carbon carrier 41.

As an option, the X-ray source 1 includes an electronics unit 7 configured to provide an acceleration voltage of at most 1.5 kV between the electron source 2 and the target layer 42, for example. It is possible that the target layer 42 and the transmission window 4 are on the same electric potential which may optionally be ground, for example, or any other voltage different from an anode voltage applied at the target layer 42.

An example of the optional electronics unit 7 is schematically illustrated in FIG. 7. The electronics unit 7 can include or can be composed of a low-voltage side 71 and a high-voltage side 72.

At the low-voltage side 71, there can be a resonant converter 73 and an electron source driver 76. On the one hand, the resonant converter 73 is connected to an electron source voltage output 75 by means of a high-voltage cascade 74 in order to provide a voltage for the electron source 2, for example, which could include a filament, like a heated filament. On the other hand, the electron source driver 76 is connected to an electron source current output 78 by means of a high-voltage transformer 77.

For example, the output voltage is 1.5 kV or less. The high-voltage cascade 74 may consist of only one stage, that is, may be or may include a rectifier. For example, the high-voltage cascade 74 includes a diode and a capacitor as well as a feedback resistor, not shown. The high-voltage

13

transformer 77 may be configured for 1.5 kV as well and could be a standard device, for example. Hence, overall the electronics unit 7 can be composed of cost-efficient devices withstanding voltages of around 1.5 kV, and no components withstanding voltages of around 5 kV as often used in X-ray sources are required.

Such an electronics unit 7 can also be present in all other examples of the X-ray source 1, especially it can also be present in the X-ray source 1 of FIG. 1.

Otherwise, the same as to FIGS. 1 to 5 may also apply to FIGS. 6 and 7, and vice versa.

Thus, concerning the X-ray source 1 of FIGS. 6 and 7, in contrast to a transmission anode as shown in context with FIG. 1, the transmission window 4 and the anode 42 could be at different potentials. However, to avoid interaction of high voltage with air, it may be desirable to operate the transmission window 4, that is, the carbon carrier 41, at ground potential. This means that for a construction with a transmission anode, see FIG. 1, the cathode at the electron source 2 is usually at negative high voltage. With a side window anode as in FIG. 6, the transmission window 4 could be operated at ground potential and the anode 42 at positive high voltage.

This means that much less circuitry is required to control the electron source 2 and the electron beam can also be controlled by applying potentials to optional electron optics. However, a distance between the transmission window 4 and the anode 42 is inevitably greater, which can change the imaging properties and may require an adjustment of an electron focusing. In practice, the side window set-up of FIG. 6 may therefore also be operated with the cathode at negative high voltage and both target layer 42 and transmission window 4 at ground potential. However, since the X-rays x do not have to be transmitted through the target layer 42 in this case, a thicker target layer 42 and a better thermal connection of the target layer 42 can be realized.

In addition, an X-ray source 1 with a low accelerating voltage of, for example, at most 1.5 kV can be realized, especially for ionization sources. Since components of the air are ionized in such an application and, for example, nitrogen is ionized first in atmospheric chemical gas phase ionization, much lower voltages or photon energies would be required for this purpose compared to conventional X-ray sources. However, since the photon yield increases with the energy of the electrons 22 and a transmission probability through the transmission window 4 also increases with the electron energy, X-ray sources 1 with 5 kV accelerating voltage and a thin beryllium window are currently used.

The use of a thin graphite membrane with a thickness, for example, of at least 0.1 μm and of at most 25 μm allows a high transmission probability of photons with low energy and, thus, the necessary accelerating voltage could be reduced. For example, with a thickness of the carbon carrier 41 of 1 μm and without any target material at the transmission window 4, one can observe a high intensity of the carbon K α -line at 277 eV. FIG. 8 shows the X-ray spectra of a corresponding X-ray source 1 for different accelerating voltages normalized to the carbon peak. The lower energy of the photons could be compensated by a correspondingly larger emission current. This would allow the X-ray source 1 to be operated at acceleration voltages even below 1 kV and still achieve a sufficient ion density for ionization applications.

Due to the lower photon energy of the generated X-rays X, a smaller penetration depth of the photons into the medium to be ionized is achieved. This enables more compact set-ups and, for example, an axial set-up in an ion

14

mobility spectrometer in which there is no danger of ionization in a drift space. Likewise, a non-radioactive electron capture detector is conceivable with such an X-ray source 1. The carbon carrier 41 and the transmission window 4 used as a graphite anode described herein is non-toxic compared to a beryllium membrane and, thus, is in general less critical in application and production.

Cost savings can also be achieved, since beryllium membranes are very expensive to manufacture. Due to the lower acceleration voltage, the circuitry can also be simplified, compare FIG. 7 which shows the simplified block diagram of parts of the drive electronics for the X-ray source 1. Due to the lower maximum voltage, either cascade stages could be saved or components with lower dielectric strength could be used compared to devices using acceleration voltages of at least 5 kV, for example. A feedback resistor (not shown) can also be used to measure the anode potential and the anode current. Said resistor would also have to withstand a lower voltage. Due to the lower number of components and simpler specifications especially in terms of voltage withstand capability, costs can be saved as well. For example, the electron source current output 78 is controlled via the high-voltage transformer 77, which then has to withstand the total acceleration voltage of around only 1 kV in this case. Furthermore, due to the lower maximum voltage either no potting is needed or smaller dimension of the device can be achieved.

In FIG. 9, an operating method is schematically illustrated. In method step M1, the X-ray source 1 is provided. Then, in method step M2, the X-ray source 1 is operated with an acceleration voltage of, for example, at most 2 kV.

Otherwise, the same as to FIGS. 1 to 8 may also apply to FIG. 9, and vice versa.

The invention described here is not restricted by the description on the basis of the exemplary embodiments. Rather, the invention encompasses any new feature and also any combination of features, which includes in particular any combination of features in the patent claims, even if this feature or this combination itself is not explicitly specified in the patent claims or exemplary embodiments.

What is claimed is:

1. An X-ray source comprising:
an electron source configured to emit electrons;
an acceleration set-up configured to accelerate the emitted electrons; and
a transmission window downwards of the acceleration set-up,
wherein the transmission window is configured to let through X-rays generated by the accelerated electrons,
wherein the transmission window is located in a straight extension of a line-of-flight of the accelerated electrons and past the acceleration set-up,
wherein the transmission window comprises a carbon carrier,
wherein the carbon carrier comprises sp₂-hybridized carbon, and
wherein the carbon carrier is an electron target and is configured to generate the X-rays of a characteristic carbon X-ray line based on being hit by the accelerated electrons.

2. The X-ray source of claim 1,
wherein a mass proportion of carbon of the carbon carrier is at least 95%,
wherein the carbon of the carbon carrier is predominantly sp₂-hybridized so that in a deconvoluted Raman spectrum of the carbon carrier a 2D-peak, in a range between 2650 cm^{-1} and 2750 cm^{-1} measured with laser

15

excitation at 532 nm, has by at least a factor of two a larger area content than a sp₃-peak in a range between 1250 cm⁻¹ and 1350 cm⁻¹.

3. The X-ray source of claim 2, wherein the carbon carrier is of pyrolytic carbon.

4. The X-ray source of claim 1,
wherein the transmission window further comprises a target layer carried by the carbon carrier,
wherein the target layer is located on a side of the carbon carrier facing the electron source, and
wherein the target layer is of at least one metal and is thinner than the carbon carrier.

5. The X-ray source of claim 4, wherein the target layer is configured to be hit by the accelerated electrons and a carbon layer is configured to be passed by the X-rays generated upon impact of the accelerated electrons on the target layer.

6. The X-ray source of claim 4, wherein the target layer is directly applied on the carbon carrier.

7. The X-ray source of claim 4,
wherein the transmission window further comprises a bonding layer, and
wherein the bonding layer is located between the target layer and the carbon carrier and is of at least one inorganic material.

8. The X-ray source of claim 4, further comprising a window frame, wherein the window frame carries the transmission window and is attached on the acceleration set-up.

9. The X-ray source of claim 1, wherein a diameter of the carbon carrier is between 4 mm and 4 cm, inclusive, and wherein the X-ray source is free of any auxiliary structures supporting a central part of the transmission window, seen in top view, where a focal spot of the accelerated electrons is located.

10. An X-ray source comprising:
an electron source configured to emit electrons;
an acceleration set-up configured to accelerate the emitted electrons; and
a transmission window downwards of the acceleration set-up,

wherein the transmission window is configured to let through X-rays generated by the accelerated electrons,
wherein the transmission window is located off a line-of-flight of the accelerated electrons and past the acceleration set-up,

wherein the transmission window comprises a carbon carrier,
wherein the carbon carrier comprises sp₂-hybridized carbon,

wherein the carbon carrier is of pyrolytic carbon,
wherein a thickness of a carbon layer is at most 10 µm,
wherein a mass proportion of carbon of the transmission window in an area configured to be passed by the X-rays is at least 90%, and

wherein the acceleration set-up is configured for an acceleration voltage of at most 1.5 kV.

11. The X-ray source of claim 10, further comprising an electronics unit configured to provide the acceleration voltage,

16

wherein a low-voltage side and a high-voltage side of the electronics unit are connected by a one-stage voltage changer.

12. The X-ray source of claim 10, wherein the carbon layer is configured to be electrically on ground.

13. The X-ray source of claim 10, wherein the transmission window is a side window, and
wherein the accelerated electrons are divertible from the transmission window.

14. An X-ray source comprising:
an electron source configured to emit electrons;
an acceleration set-up configured to accelerate the emitted electrons; and
a transmission window downwards of the acceleration set-up,

wherein the transmission window is configured to let through X-rays generated by the accelerated electrons,
wherein the transmission window comprises a carbon carrier,

wherein the carbon carrier comprises sp₂-hybridized carbon,

wherein the acceleration set-up is configured for an acceleration voltage of at most 5 kV,

wherein the transmission window is located off a line-of-flight and past the acceleration set-up so that the transmission window is a side window,

wherein the accelerated electrons are divertible from the transmission window,

wherein the carbon carrier is of pyrolytic carbon,
wherein a thickness of a carbon layer is at most 10 µm,
wherein a mass proportion of carbon of the transmission window in an area configured to be passed by the X-rays is at least 90%, and

wherein a low-voltage side and a high-voltage side of an electronics unit are connected by a one-stage voltage changer, the electronics unit is configured to provide the acceleration voltage.

15. An X-ray source comprising:
an electron source configured to emit electrons;
an acceleration set-up configured to accelerate the emitted electrons; and
a transmission window downwards of the acceleration set-up,

wherein the transmission window is configured to let through X-rays generated by the accelerated electrons,
wherein the transmission window is located off a line-of-flight of the accelerated electrons and past the acceleration set-up,

wherein the transmission window comprises a carbon carrier,

wherein the carbon carrier comprises sp₂-hybridized carbon,

wherein the transmission window is a side window,
wherein the accelerated electrons are divertible from the transmission window,

wherein a thickness of a carbon layer is at most 25 µm,
and

wherein a mass proportion of carbon of the transmission window in an area configured to be passed by the X-rays is at least 90%.
